UNITED STATES PATENT OFFICE.

GEORGE H. SELLERS, OF RIDLEY PARK, PENNSYLVANIA.

DRILL OR AUGER.

SPECIFICATION forming part of Letters Patent No. 443,297, dated December 23, 1890.

Application filed June 23, 1890. Serial No. 357,027. (No model.)

To all whom it may concern:

Be it known that I, GEORGE H. SELLERS, of Ridley Park, Delaware county, State of Pennsylvania, have invented a new and useful Improvement in Drills and Augers, of which the following is a true and exact description, reference being had to the accompanying drawings, which form a part of this specification.

My present invention especially relates to an improved twist-drill or auger formed by a rolling or forging process. The said invention, however, in its broader sense also includes a twisted or spirally-fluted drill having a central core with flanges springing spirally from around the same, however it be produced, and has its new and useful features summarized in the claims which follow this specification.

The chief object of my invention is to contrive a light but stiff, strong, and durable twist-drill or auger, and such a one as by its general shape and design may be susceptible of being manufactured from a minimum of metal and in the main by a rolling or forging process or processes, for by such preferred mode of manufacture I secure an abundant working of its several component parts and add to its even otherwise unusually great strength of form, other objects of my present invention being to so distribute the mass of the drill that corresponding members thereof may be of equal cross-section at similar parts, and thereby upon the preferred forging mode of manufacture better assure the homogeneity and strength of the drill, it being, however, here parenthetically noted that of the many modes of manufacture possible for my improved drill (whether by machinery or otherwise) the method of producing said drill by a forging process is also, so far as I am aware, of my invention and forms the subject-matter of another application for a United States patent by me, either herewith concurrently or forthwith intended to be filed in the Patent Office, and that the same, therefore, so far as it is herein alluded to, is but incidental to the most apt description which I am capable of making of my present invention, the twist-drill, and not by way of a dedication of its mode of manufacture by a forging process to the public.

Other of my objects are preferably to design, contrive, and form a "twist" or fluted drill continuous from end to end; also, to so space and form the backs of the lands which intervene between the flutes of said drill that the same may offer without detriment to the drill's self-acting chip-relieving capacity a suitable bearing for a chuck or other driver engagement; to make the drill, if need be, double-ended and without sacrifice of mass and such effective distribution of the parts as may serve to keep the drill stiff and reliable; to so fashion the lands of the drill that they may offer a minimum of material to be dressed and ground when pointing and edging the drill; to brace the flanges or lands of the drill by means of merging and combining them with a central core or stiffener, and to give the flanges such number and "pitch" (rapidity of twist) as shall serve for the proper support of their edges, and also insure the prompt removal of chips from their cutting-faces when at work, and preferably, also, to give such tapering form to the bodies of these lands when viewed in cross-section as may serve the better to assist their manufacture between rolls in a preliminary stage of the preferred forging process aforesaid, together with such preferred form of the central core and other parts as will be best understood by reference to the following detailed description.

Reference now being had to the accompanying drawings, forming part of this specification, in which similar letters of reference indicate corresponding parts throughout the several figures, they will be found to illustrate my said improvement in twist-drills as follows, to wit:

Figure 1 is a side elevation, which shows the point and the portion of the shank of one of my improved twist-drills in its preferred form. Fig. 2 is a similar side elevation of a similar drill having a modified form of edge. Fig. 3 is a general side view of my improved drill in its preferred form, with both ends pointed and edged, the point upon the right-hand extremity of the drill being, however, represented as sharpened without having the cutting-edges carried to the extreme center of the drill, as the edges upon the left-hand point are represented as being. Fig. 4 is a

cross-section upon a slightly-larger scale of the drill shown in Fig. 3, the plane upon which it is taken being indicated by the broken line $x\ x$. Fig. 5 is an end view of the preferred form of cutting-point, or that shown upon the left-hand end of the drill represented in Fig. 3. Fig. 6 is a cross-section through the body of a modified form of the drill. Fig. 7 is a side view corresponding to Fig. 3 of a further modification, wherein there are three flanges springing from the common central core instead of four, as are shown in all the preceding figures. Fig. 8 is a cross-section, also upon a slightly-larger scale, of the drill shown in Fig. 7 by a plane passed upon the line yy of said figure; and Fig. 9 is a side elevation which shows the point and adjoining portion of the shank of the device when specially contrived as an auger.

In general, as shown in the figures, the drill D consists of two chief sets of elements—one a single central and, as it were, columnar support or core D', while the other comprises three or more lands or flanges $d\ d'\ d''\ d'''$, &c., all arranged in a series merging in and rising from the said common core, with and about which core they all, at equal interspace and preferably uniform pitch, wind in a helix or spire. The said lands' being of uniform dimensions, numerous, and lying parallel to the axis of the core, give a fluted cylindrical outline to the whole. The backs b of the lands also, by approximating, if they do not actually conform to, equivalent areas of a true cylindrical body of equal diameter, prevent the passage of the drill through any orifice other than a circular one—that is, they prevent such passage unless the drill-shaft thus formed be rotated in conformity to the pitch of its screw-like body, when of course it may be possible to pass it through a cross-shaped opening substantially corresponding to the profiles of its flanges and core when viewed endwise or viewed as shown in Fig. 5. Such opening and rotation in precise conformity to the pitch of the screw are, however, it is almost needless to say, extremely unlikely events to happen with ordinary drill feeding and driving, and therefore the drill may in substance be said to be one which cannot pass through an opening less than or in any wise materially varying from that which it is in point of fact calculated to bore and fashion—viz., a cylindrical or circular aperture. While I prefer the pitch of the lands to be uniform and their number to be four, with an equal spacing of nine degrees from center to center, and the cross-section of the drill's core, as shown by dotted lines in Fig. 4, to be a substantially octagonal figure, the alternate sides of which merge into or are integral with the base of one of the drill's flanges, as will be readily seen from reference to that figure, I do not wholly limit my improved drill's body or shaft to that precise form or number of flanges, though I much prefer it when so fashioned; and for the sake of further illustration I have therefore shown

the modifications, Figs. 6, 7, and 8, in the former of which, Fig. 6, there is a drill of strictly cruciform cross-section—that is to say, one the four flanges of which do not taper as they pass outward from their common supporting-core, into which core they merge in this case by coves or circular arcs of small radius for the sake of strength, although of course they may, as indicated by dotted lines p , meet the same along sharp re-entrant flute-angles—say of ninety degrees each.

In Fig. 8 a drill of my improved sort is shown reduced to one with a substantially cylindrical core having three flanges $d\ d'\ d''$, spaced at one hundred and twenty degrees to each other upon any common plane of cross-section, thereby sacrificing certain of the more meritorious features of the preferred straight or St. Andrew's cross sort shown in Figs. 1, 2, 3, 4, 5, and 6, for it is evident upon inspection of Fig. 8 that the cutting-edges of such a drill or any other in which the flanges are not arranged in pairs each member of which is substantially diametrically opposite to its mate, or as shown in Figs. 4, 5, and 6, cannot act upon what is commonly known as the "duplex" and most advantageous method of cutting with drills and boring tools for keeping them true to an established line of advance. However, Figs. 7 and 8 illustrate a drill which will be found in practice to operate with many advantageous results, and, in common with Figs. 1, 2, 3, and 5, shows how my improved boring device, whatever the number of its flanges or the shape of its core may be, can be advantageously pointed and sharpened for metal-working or as a drill proper.

I preferably make the drill or auger, as above alluded to, from a "billet" of "tool-steel" (or such steel as is proper to make an ordinary edged tool from) and by any suitable forging operation—such as taking a sufficient heat upon the billet and passing it one or more times through a suitably-formed groove or grooves in a nest of rolls, fashioning it into a straight blank of uniformed-shaped cross-section throughout its length, and then, and if possible at the same heat, twisting this straight blank to a proper pitch and the multiple-thread screw-like form of twisted blank, which is now substantially clear. This latter act of twisting the blank may be done by a good smith with a mere vise and tongs or wrench-hold and give fair results; but I preferably do it by such twisting tools and dies as it is not necessary to here particularly describe, since those which I find give the best results are fully described by me in my application or applications for patent for the method of making these drills above mentioned; and, finally, as a completion of the forging I preferably straighten and size such incipient drill or auger blank, as by rolling the same between a relatively-adjustable platen and a reciprocating pressure plane plate. Otherwise I have fashioned

these blanks by planing or milling out the flutes and so obtaining either a straight or appropriately spiral blank, and, according to its straight or twisted character at this stage, 5 subsequently proceeding in substantially the like manner as in the preferred forging method. The pitch of the spire is, I find, with a drill of one inch diameter and four flanges, best if of about two and one-half inches.

10 However, it may be more or less steep, and, if need be, as is well understood by twist-drill and auger makers, of gaining or non-uniform pitch. The final stages in all cases consist of pointing or otherwise dressing the working 15 end or ends of the drill or auger to an appropriate shape, then hardening, tempering, and edging the same in order to produce the completed article.

The pointing for drills preferably is a conical one—say of sixty degrees—and the sharpening, which of course is done after the drill has been wrought, hardened, tempered, and otherwise prepared in a proper manner for the production of drills, is best effected, as I contrive it, by grinding upon the flange's extremities proper angles of relief and cutting-edges, and further preferably supplementing the length of the drill's several flanges and cutting-edges by carrying these edges *e* in a proti-

30 longation of each curved flange forward to the center of the core, as by means of what I may call "conoidal" recesses *c*, ground into the coned point of the core *D'*. This will be easily understood by referring to Figs. 1 and 35 5, where the mode of sharpening is the proper one for boring into iron or steel, and where the core of the drill is shown by such recesses *c*, fashioned in the manner of a rose-drill. By this means the cutting-edges are

40 made to seek and converge in a common center, which of course materially facilitates the ease with which the drill may be fed. However, referring to the right-hand extremities of Figs. 3 and 7, the drill will be seen, in both 45 the three and four flange varieties, to be sharpened in such way as to have the edges and faces of relief terminating short of the central core, which is here, save only for the quasi cutting action of the somewhat pyramidal arrangement of the point of the core, necessary to force through the work without the best cutting action, in which respect the drill more nearly corresponds to the action of ordinary drills than it does when fashioned 50 with the preferred rose-sharpening aforesaid.

In Fig. 2 the rear walls of the flanges are not ground away with relief-faces, but the front flanges are truncated by grinding them transverse to the general mass of each particular flange, thus giving the requisite obtuse sharpening proper for boring into brass and similar material. The core *D'* in this case is also dressed away in the region of the point to a cylindro-conical or rifle-bullet-like shape, 55 thus giving a chance to grind the cutting-edge of each flange to approximately its point of common intersection with the others.

A striking advantage flowing from the uniformity of my improved drill or auger's mass, as aptly illustrated by the typical cross-section shown in Fig. 4, resides in the fact that thereby the hardening and tempering processes act uniformly and equally throughout the whole body of the drill, and if broken away at its edges it may be quickly repaired 75 by a mere grinding.

For an auger an appropriate form of pointing is shown in Fig. 9, where the blank is here represented as having had its flanges dressed or cut back from the leading end of the core, which, so far as it protrudes, is fashioned into an ordinary auger-like-head screw-point *S*. The cutting-edges *e* of the flanges shown in Fig. 9 are also here of proper acute-ness to act upon wood and, in reference to 85 the general mass of the drill are located at a preferred square position to the core *D'* and all in a common plane. The edges may also, as indicated by dotted lines at *KK*, have marginal guide-lips in the manner of ordinary 90 augers, but with the preferred four-flange sort. This is, I find, an almost unnecessary addition.

Having now fully described my invention, what I desire to claim and secure by Letters 95 Patent of the United States is—

1. As a new article of manufacture, a twist-drill consisting of a central core and fashioned integral therewith and rising therefrom at substantially equal interspace three or more 100 flanges of similar width, the whole spirally twisted and adapted to be pointed and sharpened, substantially as described.

2. As a new article of manufacture, a twist-drill consisting of a central core and three or more helically-wound flanges rising integral therewith and continuously along the same from end to end, substantially as described. 105

3. As a new article of manufacture, a drill consisting of a single forged body comprising 110 a central core of substantially octagonal cross-section, as described, and rising therefrom and merging therewith upon alternate faces of said octagon similar and outwardly-tapering flanges, the whole being helically twisted 115 and adapted to be pointed and sharpened at one or both ends, substantially as described.

4. As a new article of manufacture, a drill consisting of a single forged body comprising a central core of substantially octagonal cross-section, as described, and rising therefrom and merging therewith upon alternate faces of said octagon similar and outwardly-tapering flanges, the whole being helically twisted, 120 pointed, and sharpened, the latter by fashioning suitable cutting-edges and relief-faces upon the ends of said flanges when pointed, and also by carrying the same to a common center by means of recessing or rose-pointing the said core, substantially as described. 125
